UNITED STATES PATENT OFFICE.

CHRISTIAN H. WAGNER, OF TIFFIN, OHIO.

TOOL.

1,421,871.

Specification of Letters Patent.

Patented July 4, 1922.

Application filed April 16, 1921. Serial No. 461,742.

To all whom it may concern:

Be it known that I, CHRISTIAN H. WAGNER, a citizen of the United States, residing at Tiffin, in the county of Seneca and State of Ohio, have invented new and useful Improvements in Tools, of which the following is a specification.

This invention relates to tools of the class generally designated as pliers, an object of 10 the present invention being to provide a pair of pliers which are especially adapted for the insertion and removal of cotter-pins.

Another object of the invention is the provision of a tool of this character which may 15 be used for handling cotter-pins, nails, wire, and the like of any length, the tool being so constructed that the article handled may extend beyond each end of the gripping jaws.

Another object of the invention is the 20 provision of a pair of pliers whose gripping jaws are offset and provided with a longitudinally extending opening for receiving a cotter-pin tool which includes means for engagement with the eye of the pin, together 25 with means for holding the said engaging means against accidental removal.

With the above and other objects in view, the invention further includes the following 30 novel features and details of construction, to be hereinafter more fully described, illustrated in the accompanying drawings and pointed out in the appended claim.

In the drawings:

Figure 1 is a plan view of a tool embodying the invention,

Fig. 2 is an edge view of the same,

Fig. 3 is a fragmentary view showing the manner of gripping a cotter-pin,

Fig. 4 is a similar view illustrating the engagement of the tool with the eye of a cotter-pin, and

Fig. 5 is a detail sectional view on the line 5—5 of Fig. 1.

Referring in detail to the drawings, where 45 in like characters of reference denote corresponding parts, the tool is illustrated as formed of a pair of pivotally connected members which include handles 1 and 2 and jaws 4 and 5, the latter jaw being a part of the pivoted member which carries the handle 1, while the jaw 4 is carried by the member which includes the handle 2. The pin for

pivotally connecting the members together is indicated at 3.

The jaws 4 and 5 are offset as shown in 55 Fig. 2 of the drawings, and this offset portion is provided with openings 7 and 8 which extend transversely through the jaws and provide gripping noses 4^a and 5^a, arranged upon the jaws 4 and 5 respectively. These 60 noses are provided with longitudinally extending V-shaped grooves in their opposed faces, the said grooves registering when the jaws are closed so as to provide a rectangular opening 6 for the reception of the cotter-pin 65 or other object, the recesses 7 and 8 being designed to receive the head or eye of the pin, as will be clearly understood. The recesses 7 and 8 are disposed longitudinally of the jaws 4 and 5 and extend from the gripping 70 noses to the inner ends of the offset portions of the jaws, so that in handling an unusually long article such as a long pin, nail, wire or the like, its ends may extend beyond each end of the jaws, so that the use of the tool in 75 this respect is unlimited. By offsetting the jaws as shown in the drawings, the latter may be used under conditions not otherwise permissible.

The handles 1 and 2 are of sufficient length 80 to provide proper leverage, and the extremity of the handle 1 is formed with a right-angled extension which is preferably of rounded tapered formation as shown, and is adapted to be received within a notch 11 85 provided in the extended end 10 of the handle 2. The extremity 9 is designed to be inserted in the eye of a cotter-pin as shown in Fig. 4, and if desired the end 10 of the handle 2 may be closed over the extremity 9 and the pin securely held thereon. This is especially convenient in removing tight or bent pins. In addition, the members are provided with transversely arranged openings 12 and 13, which, when the jaws are closed are out 90 of register. By slightly opening the jaws these openings may be brought into register to provide the cutter.

The tool is susceptible of various other uses and contains many advantages over 100 tools of this character heretofore manufactured. It is susceptible of various changes in minor details of construction, and the right is therefore reserved to make any and

all changes that properly fall within the scope of the appended claim.

Having described the invention what is claimed is:—

5 A tool embodying a pair of pivotally connected members, handles at one end thereof, and a pair of offset jaws located at the opposite end, said jaws having transversely ar-

ranged openings therethrough and providing inwardly extending gripping noses, and 10 the said openings extending from the gripping noses to the inner ends of the offset to provide an open-ended longitudinally-disposed recess.

In testimony whereof I affix my signature. 15
CHRISTIAN H. WAGNER.
